US00D502964S

(12) United States Design Patent (10) Patent No.: **US D502,964 S**
Cziraky (45) Date of Patent: **** Mar. 15, 2005**

(54) PORTABLE EASEL

(75) Inventor: **David A. Cziraky**, Bethlehem, PA (US)

(73) Assignee: **Binney & Smith Inc.**, Eaton, PA (US)

(**) Term: **14 Years**

(21) Appl. No.: **29/193,498**

(22) Filed: **Nov. 10, 2003**

(51) LOC (7) Cl. **19-06**

(52) U.S. Cl. **D19/36; D19/52; D21/469**

(58) Field of Search **D21/469; D19/59, D19/65, 35, 36, 52, 78, 81-85, 86-88, 90, 91, 99, 100; 434/81, 84, 85, 87, 88, 90, 91, 98, 408-410, 414-420, 424, 425; 248/441.1, 450-452, 460-461**

(57) CLAIM

The ornamental design for a portable easel, as shown and described.

DESCRIPTION

FIG. 1 is a front perspective view of a portable easel in the closed position.

FIG. 2 is a front perspective view of the portable easel in the opened position.

FIG. 3 is a rear perspective view of the portable easel in the opened position.

FIG. 4 is top plan view of the portable easel in the closed position.

FIG. 5 is rear elevational view of the portable easel in the closed position.

FIG. 6 is a front elevational view of the portable easel in the closed position.

FIG. 7 is a bottom plan view of the portable easel in the closed position.

FIG. 8 is a first side elevational view of the portable easel in the closed position.

FIG. 9 is a second side elevational view of the portable easel in the closed position.

FIG. 10 is a front elevational view of the portable easel in the opened position.

FIG. 11 is a top plan view of the portable easel in the opened position.

FIG. 12 is a rear elevational view of the portable easel in the opened position.

FIG. 13 is a first side elevational view of the portable easel in the opened position; and,

FIG. 14 is a second side elevational view of the portable easel in the opened position.
